UNITED STATES PATENT OFFICE

FLORENCE B. MACCARTHY, OF MARYSVALE, UTAH

DIAL-TELEPHONE LOCK

Application filed October 22, 1928. Serial No. 314,250.

This invention relates to locks for preventing the use of telephones for outgoing calls where the telephones are provided with dials.

The invention comprises a padlock adapted to interlock with the dial plate so as to prevent the turning of the dial far enough to register a call.

An embodiment of the invention is illustrated in the accompanying drawing, in

10 which

Figure 1 represents a plan view of a telephone base equipped with a dial and lock.

Figure 2 is a side view, and

15 Figure 3 is a perspective view of the padlock.

A telephone base 1 has the usual supporting column 2 for holding the transmitter and receiver (not shown) and a call dial 3. A lock case 4 having a key operated member 5 adapted to be thrown by a key inserted in a suitably placed keyhole 6 has a long arm 7 and a shorter arm 8 extending from its base.

To apply the lock to the dial, the longer arm 7 is first inserted in one of the dial holes, for example, the hole over the letters J. K. L., the lock being presented in the position shown in dotted lines in Figure 1. In this position the arm 7 can be slid under the outer rim of the dial until an offset shoulder 9 on the arm is

30 allowed to pass down into the hole. The lock can then be turned until the arm 8 is over another of the dial holes, for example, the one designated P. R. S., in which position the arm 8 can be pushed down into this hole and then by a retractive movement, the arm 8 is made to engage under the dial, its rearward movement being checked by a shoulder 10 coming against the edge of the dial hole. When in this position, the key is turned and

40 the bolt 5 is thrown into an intermediate hole in the dial, for example, the one designated M. N. O., the location of the bolt 5 in the lock being such as to prevent the lock being moved either forward or back. The lock thus becomes a rigid part of the dial. The arm 7, projecting as it does beyond the periphery of the dial, is made long enough to impinge against the supporting column 2 when an attempt is made to turn the dial, and by thus interfering with the free turning of the dial, it

acts as a stop and prevents the dial from functioning. While I have shown the stop member 7 as impinging against the column 2, it is evident that any other projection may be used to interfere with its free motion. It will be noticed that while the lock presents a means of preventing the use of the telephone for outgoing calls, it nevertheless interferes in no way with the receipt of incoming messages.

I claim:

1. A lock for dial telephones adapted to be removably mounted upon a telephone dial, said lock having a key-operated bolt to engage one of the holes of the dial, and a stop member adapted to engage in another of the holes of the dial and project from the dial to engage a fixed part of the telephone to limit the movement of the dial.

2. A lock for dial telephones comprising in combination a telephone base and column, a lock having a key operated member adapted to engage in one of the holes of the dial, and a stop member adapted to engage in another of the holes of the dial, said stop member being locked to the dial by the key operated member and extending beyond the periphery of the dial far enough to impinge against the column to prevent the turning of the dial.

3. A lock for dial telephones comprising in combination a dial telephone having a base upon which a dial is mounted rotatably, a column rising from the base, a dial lock having a lock case containing a key operated member, projections on the case adapted to enter two holes in the dial and lock therein when the key operated member is thrown, one of the said projections being adapted to impinge against the said column to prevent the operation of the dial.

4. A lock for dial telephones adapted to be removably mounted upon a telephone dial, said lock having a bolt to engage one of the holes of the dial, a stop member adapted to engage in another of the holes of the dial and project from the dial to engage a fixed part of the telephone to limit the movement of the dial, and key-actuated means for disengaging said bolt from a dial hole.

FLORENCE B. MACCARTHY.
